US0D1043992S

(12) **United States Design Patent** (10) Patent No.: **US D1,043,992 S**
(45) Date of Patent: ** Sep. 24, 2024

(54) **EYE TESTING APPARATUS**

(71) Applicant: **TowardPi (Beijing) Medical Technology Ltd.**, Beijing (CN)

(72) Inventors: **Xiao Han**, Beijing (CN); **Zhiqiang Zhao**, Beijing (CN); **Ranran Cao**, Beijing (CN); **Juan Li**, Beijing (CN); **Yanhui Zhao**, Beijing (CN); **Xiao Wang**, Beijing (CN)

(**) Term: **15 Years**

(21) Appl. No.: **35/518,001**

(22) Filed: **May 4, 2023**

(80) **Hague Agreement Data**

Int. Filing Date: **May 4, 2023**

Int. Reg. No.: **DM/230504**

Int. Reg. Date: **May 4, 2023**

Int. Reg. Pub. Date: **Aug. 4, 2023**

(30) **Foreign Application Priority Data**

Jan. 12, 2023 (CN) 202330035158.2

(51) LOC (14) Cl. **24-02**

(52) U.S. Cl.

USPC **D24/172**

Primary Examiner — Rhea Shields

(57) **CLAIM**

The ornamental design for an eye testing apparatus, as shown and described.

DESCRIPTION

1. Eye testing apparatus

1.1 : Perspective

1.2 : Perspective

1.3 : Front

1.4 : Back

1.5 : Left

1.6 : Right

1.7 : Top

1.8 : Bottom

1.9 : Enlarged

The broken lines shown in the figures depict portions of the eye testing apparatus that form no part of the claimed design; the dot-dash broken lines in figs. 1.1, 1.9, and the label “1.9” in fig. 1.1 are for the purpose of depicting the cut line of the enlarged view and form no part of the claimed design.

1 Claim, 9 Drawing Sheets
